UNITED STATES PATENT OFFICE.

ERNEST D. ANDERSON, OF NEW YORK, N. Y.

GAS-LIGHTER.

SPECIFICATION forming part of Letters Patent No. 698,427, dated April 29, 1902.

Application filed July 2, 1901. Serial No. 66,834. (No model.)

To all whom it may concern:

Be it known that I, ERNEST D. ANDERSON, a citizen of the United States, residing in the city of New York, borough of Manhattan, county and State of New York, have invented a certain new and useful Improvement in Gas-Lighters, of which the following is a specification.

My invention relates to gas-lighters, particularly of the kind adapted for attachment to burners and in which there is used a substance or pellet which has the property of absorbing gas and becoming sufficiently heated by this absorption to cause an ignition of the gas.

The object of my invention is to provide a cap or attachment adapted for use in connection with any gas-burner which will be simple, durable, and which particularly will be so constructed that the user cannot fail to put on the attachment in the proper position.

The invention will be fully described hereinafter and the features of novelty pointed out in the appended claims.

Reference is to be had to the accompanying drawings, in which—

Figure 1 is a side elevation of a burner provided with my improved attachment. Fig. 2 is a sectional elevation thereof on line 2 2 30 of Fig. 5. Fig. 3 is an elevation seen from the opposite side to that shown in Fig. 1. Figs. 4 and 5 are sectional plans on line 4 5 of Fig. 2, showing my improved attachment applied to burners of all forms; and Fig. 6 is a sectional elevation of the attachment applied to a burner of the form shown in Fig. 5.

The improved attachment comprises a body A, which is of the shape of approximately a half-cylinder and has connected with it on the opposite side a spring-tongue A', which when the attachment is separate from the burner ranges obliquely toward the lower end of the body A, so that said tongue exerts sufficient pressure to hold the attachment in place on a burner of any shape or size. The lower end of the tongue is preferably bent outward, as shown at A'', to facilitate its manipulation. In order to positively determine the position of the body A and of the entire structure forming my attachment, the upper part A³ is formed cylindrically and is surmounted by a cap A⁴, it being understood that

a shoulder is formed between the cylindrical portion and the spherical cap. This shoulder forms a stop against which the upper end of a square burner abuts, and it thus is impossible to give the attachment a wrong position if the simple instructions are followed that the attachment should be slipped over the burner and moved down as far as it will go. 55 The cap A⁴ has a slit A⁵, through which the gas is adapted to escape. When a round burner is used, as in Fig. 6, the top or cap A⁴ forms the stop engaged by the burner.

To the member A of the attachment is secured a spiral B, preferably by passing one end of the spiral B through straps A⁷, formed by bending portions of the body A outwardly. The other end of the spiral B carries any suitable catalytic substance or igniting substance 70 D, preferably supported on a carbon block C. The particular substance used forms no part of my invention. The inward movement of the arm B² is limited by the projection A⁶, struck up from the cap A⁴ at the slit A⁵. 75

In applying the attachment to a round burner E³, Fig. 5, having the customary slit E⁴, the slot A⁵ should be placed parallel with the slit E⁴. When a so-called "square" burner E, with aperture E', is used, Fig. 4, the apertures should be placed crosswise of the slot A⁵.

It will be understood that when the gas-cock is opened the catalytic substance D will become heated by absorption and will ignite the gas in the well-known manner. The heat 85 being communicated to the spiral B, the latter will expand, causing the arm B² to swing outward, as indicated by the arrow, thus carrying the igniting substance D away from the flame, and thus preserving it from carbonization and other deteriorating influences. When the gas is turned off, the spiral being no longer heated will contract, thus swinging the igniting substance D back into position for the next action. The lug A⁶ forms a stop 95 for the arm B² and prevents too strong a contraction of the spiral.

The proper adjustment of the cap, as already stated, should be made in such a manner that the slot A⁵ is placed parallel with the slits of the burners or parallel with the plane of the flame. If the cap is fixed on the burner in any other position, my invention will operate in the same manner as it operates when the

cap is properly adjusted by reason of the fact that the pill C is fastened at an angle to the cap, so that it is always in the path of the stream of gas or so near it as to act correctly.

5 When the cap is not properly adjusted over the slits of the burners, the shape of the flame is changed to a variety of unusual forms and the attention of persons using the light will be speedily called by this means to shift the

10 cap to the proper position.

I claim as my invention—

1. A lighting attachment for gas-burners comprising a body arranged to embrace the burner, an apertured cap at the upper end of said body, the cap and body forming together a shoulder to limit the downward movement of the attachment, and an igniting substance carried by said attachment.
2. A lighting attachment for gas-burners comprising a body arranged to contact with the burner, a spring-tongue arranged at the opposite side to the said body, a cap connected with the upper ends of the body and of the tongue, said cap being apertured for the passage of gas and a lighting substance carried by the attachment.

3. In a gas-lighter, the combination of the supporting-body with a spiral having its inner end extended outwardly beyond the coils lengthwise of the body and fastened thereto, 30 the coils being arranged in front of said end, and a lighting substance carried by the outer end of the spiral.

4. In a gas-lighting attachment for burners the combination of a slotted cap and means 35 for attaching it to the burner with a spiral secured to said cap, a lighting substance carried by the spiral and a stop to limit the movement of that part of the spiral which carries the lighting substance.

5. In a gas-lighter, the combination of the supporting-body having portions bent outwardly to form straps, with a spiral having its inner end extended through said straps and its coils arranged in front of said inner 45 end, and a lighting substance carried by the outer end of the spiral.

ERNEST D. ANDERSON.
